UNITED STATES PATENT OFFICE.

ALFRED C. ABRAMSON, OF ROCKFORD, ILLINOIS, ASSIGNOR TO THE EAST ROCKFORD MANTEL COMPANY, OF SAME PLACE.

DESIGN FOR A MANTEL.

SPECIFICATION forming part of Design No. 24,156, dated March 26, 1895.

Application filed February 23, 1895. Serial No. 539,491. Term of patent 3½ years.

To all whom it may concern:

Be it known that I, ALFRED C. ABRAMSON, a citizen of the United States, residing at Rockford, in the county of Winnebago and State of Illinois, have invented and produced a new and original Design for Mantels; and I do hereby declare the following to be a full, clear, and exact description of the same, reference being had to the accompanying drawing, forming a part thereof.

The figure of the accompanying drawing is an isometric view of the new design for mantels.

The design consists in a mantel of substantially the configuration shown provided with a supplemental shelf resembling a miniature balcony situated on each side of a paneled frame above the mantel shelf and supported conjointly by said frame and by a column resting on the mantel shelf over the columnar shelf support. This arrangement imparts an idea of solidity in the balcony support and the effect is pleasing. Each balcony has an outline curved outwardly and continuously from its junction with the frame to a point nearly over a column. The side opposite the column and curved side joins the frame. Said two sides are connected by a portion ex-

tending from the frame to the outer end of said curve a little in advance and outside of the capital of the balcony-supporting column.

Numerals 1 denotes the mantel shelf and 2 the balconies.

3 is the curved outline of the shelf or balcony and 4 denotes balusters. The balusters 4 are arranged in a straight line parallel with the straight portion 5 of the edge or outline of the balcony.

Above each balcony is a plain panel 6, a fluted surface 7 and a battlement foliation 8. Between these latter is a shelf or cornice 9 supported by brackets 10.

The mantel shelf 1 at each end surmounts a rectangular column 11 having an elongated capital ornamented with a foliation and a fluted surface.

What I claim is—

The design for a mantel as shown and described.

In testimony whereof I affix my signature in presence of two witnesses.

ALFRED C. ABRAMSON.
